His ATTORNEY.

UNITED STATES PATENT OFFICE.

HOWARD H. DUDLEY, OF KANSAS CITY, MISSOURI.

SUPPORT FOR THE CROSSING-RAILS OF RAILROADS.

No. 905,299.

Specification of Letters Patent.

Patented Dec. 1, 1908.

Application filed June 29, 1908. Serial No. 441,027.

To all whom it may concern:

Be it known that I, HOWARD H. DUDLEY, a citizen of the United States, residing at Kansas City, in the county of Jackson and State of Missouri, have invented certain new and useful Improvements in Supports for the Crossing-Rails of Railroads, of which the following is a specification.

My invention relates to an improved support for the crossing rails of railroads and the method of constructing the same.

The object of my invention is to provide a crossing support which will firmly support the rails and will not readily permit the entrance of water into the ground under the support, which will firmly retain its position, and which can be economically constructed.

Another object of my invention is to provide a method for constructing a crossing support which can be quickly and economically carried into effect, and which will provide a support practically impervious to the entrance thereunder of moisture.

Other novel features of my invention are hereinafter fully described and claimed.

In the accompanying drawings illustrating my invention, Figure 1 is a perspective view of my improved crossing support, portions of the ties and ballast being broken away. Fig. 2 is a vertical sectional view on the dotted line *a*—*b* of Fig. 1. Fig. 3 is a top view of the concrete base, a portion of which is broken away to disclose the channels for the webs.

Similar characters of reference denote similar parts.

1 denotes the crossing rails mounted upon horizontal cross ties 2 which in turn are supported upon ballast 3 of broken rock or similar material.

The ballast 3 is mounted on a horizontal base 4 of cementitious material, such as concrete. The base 4 is provided with vertical webs 5 which extend downwardly into channels 6 cut into the ground to receive them. The webs 5 are preferably at the edges of the base 4 and serve to keep moisture from passing under the base at its edges. They also serve to prevent lateral movement of the base upon the ground.

In constructing the crossing the channels 6 are first dug in the ground, after which

sheet between and extending into and filling the channels. Upon the base so formed is placed ballast of broken rock or similar material, and upon the ballast are placed horizontally the ties 2 which support the crossing rails 1.

By the insertion between the ties and the concrete base of the ballast danger of breaking of the base by train pressure on the rails is eliminated and a more flexible support for the rails is provided.

My invention may be modified, within the scope of the appended claims, without departing from its spirit.

Having thus described my invention, what I claim and desire to secure by Letters Patent, is:—

1. A crossing support comprising ties which support crossing rails, a horizontal cementitious base, and ballast supported on said base and supporting said ties.

2. A crossing support for rails comprising a base of cementitious material having a horizontal body provided with one or more vertical webs, ballast mounted on said base, and horizontal ties supported on said ballast and supporting the crossing rails.

3. A support for crossing rails comprising a base of cementitious material having a horizontal body and a plurality of downwardly extending webs some of which are disposed at angles to others, ballast supported upon said base, and horizontal ties supported on the ballast and supporting the crossing rails.

4. A support for crossing rails comprising a base of concrete, ballast mounted on said base, and horizontal ties supported on said ballast and supporting the crossing rails.

5. A support for crossing rails comprising a horizontal concrete base having one or more vertical webs extending downwardly, ballast mounted on said base, and horizontal ties supported on said ballast and supporting the crossing rails.

In testimony whereof I have signed my name to this specification in presence of two subscribing witnesses.

HOWARD H. DUDLEY.
